DETACHABLE BIT FOR DRILLS
AND THE LIKEJohn Ronald MacDonell, Falconbridge,
Ontario, CanadaApplication April 16, 1935, Serial No. 16,711
In Canada February 20, 1935

4 Claims. (Cl. 255—64)

My invention relates to new and useful improvements in drill shank and detachable bit, for power drills.

Power drills used in mining, excavating, etc., are subject to constant pounding and hard use.

5 It is estimated that the bit on a drill will last from three to six feet of digging, while the drill shank is good for approximately 400 ft. to 600 ft. of digging before it crystallizes and has to be replaced. It will therefore, be apparent that it 10 is essential to have a detachable bit that can be easily replaced, so that the drill shank can be retained for its full life.

15 Various detachable bits are in use at the present time, but, my invention covers improvements in the construction of the bit and drill shank, and in the means for coupling them together.

The primary object of my invention is to provide a drill shank with a detachable bit, to lengthen the life of the drill.

20 A further object is a connection between bit and drill shank that is safe and reliable.

Another object is an easy means of coupling bit to drill shank without the use of tools.

25 A further object is to prevent splitting or breaking of drill shank when in use.

A further object is to prevent drill shank and bit becoming locked or riveted together.

30 A further object is to provide means for cooling bit when in operation, and for disposing of the water, dirt, etc., when digging.

35 With these and other objects in view that may be apparent as the description proceeds, the invention consists in the novel arrangement of parts as hereinafter more specifically set forth, claimed and shown in the accompanying drawings, forming a part of this present application, and in which—

Fig. 1 is a side elevation of the drill and bit joined together.

40 Fig. 2 is a perspective view of drill and bit being coupled together.

Fig. 3 is a side elevation of bit alone.

45 Fig. 4 is a perspective view of drill alone, showing one design for coupling it with bit.

Fig. 5 is a perspective view of the reverse side of Fig. 4.

Fig. 6 is a side elevation of an alternative design for bit.

50 Fig. 7 is a perspective view of drill showing an alternative design for coupling with bit.

Fig. 8 is a perspective view of the reverse side of Fig. 7.

55 Fig. 9 is a cross section view on Fig. 1, along lines 9—9.

Referring more in detail to the drawings in which similar reference characters designate corresponding parts, it will be seen that the invention consists of—

A drill made in two sections, a drill shank 1, and a bit 2. These two parts are coupled together by inserting one end of the drill shank 1, inside the bit 2, through an opening 3, in the side of bit 2. A right angle cut 4, on each side of drill shank slides over a pair of small projections 5, inside the bit and the drill 1, then slides down inside 10 the bit 2, into hollow portion 6.

A hole 7 runs the length of the drill 1, to allow cooling water to flow through the bit, and opening 8, in bit 2 allows the water to continue to the face of the bit to cool it while cutting. A notch 15 9 in the centre of cutting face 10, allows the water to flow out. The bottom of bit 2 is cut away on four sides at 11, providing a series of cutting edges arranged at right angles to the cutting face 10 and the beveled sides allow the water grit and 20 dirt to by-pass up past the bit. Bit 2 is tapered slightly toward the top.

The drill shank 1, may be tapered slightly at one end as at 12, or at both ends. By tapering the shank the bit will slide on easily and tighten 25 up at the top after drilling for a time should the end of drill shank become knurled it will still remove easily.

The right angle cuts 4, are at both ends of the drill shank so that the bit 2 may be attached to 30 either end. The four edges of drill shank are chamfered at 13.

It will be noted the distance between the cut 4 and end of the shank is greater than the depth of the opening 3 and in order to connect or detach bit 2, the drill shank 1 has to be bent over at an angle to insert or remove the shank from the side of the bit. There is no chance of the bit coming off the drill while digging, as it is necessary to first pull the bit down and bend it 40 over on an angle to allow the projections 5 to slip out of angle cuts 4.

An alternative style of bit is shown in Fig. 6. This bit is similar to the other except the bottom is cut away on two sides, shown at 14, and small 45 notches 15, allow the water, dirt, etc., to by-pass up past the bit.

An alternative drill shank is illustrated in Figs. 7 and 8. This drill is similar in construction except the cuts 16, on each side of shank and at both ends are in a V shape, with the opening pointing upward. This makes the connection with bit 2 even more secure so the drill cannot become detached from bit.

It will be seen from the foregoing that this 55

novel method of connecting bit to drill is decided advantage in this type of drilling to insure a safe and convenient connection.

I claim:

- 5 1. In combination a drill shank for power drills with detachable cutting bit, grooved indents, in the sides of said drill shank, cut diagonally downward and joining vertical grooves, said grooves forming a dependable connection with corresponding projections inside said cutting bit interlocking said drill shank and bit, a tapered end on said drill shank insuring easy removal of said bit, means for cooling cutting edge of said bit, means for by-passing residue up past bit while drilling, substantially as described.
- 10 2. In combination, a drill shank for power drills having vertical grooves in the sides thereof, intersecting lateral grooves opening through one edge of the shank, a bit having a socket to receive the end of said shank, said socket having an opening through the side thereof for insertion
- 15 20

of the shank in a lateral direction and projections on the walls of the socket for interlocking engagement with the grooves of said shank.

3. In combination, a drill shank for power drills having vertical grooves in the sides thereof closed at both ends and intersecting lateral grooves opening through one edge of the shank, a bit having a central socket to receive the end of said shank, said socket having an opening through the side thereof for insertion of the shank in a lateral direction and projections on the walls of the socket for interlocking engagement with the grooves of said shank. 5

4. In combination, a drill shank for power drills having diagonal grooved indents in the sides of said shank merging with vertical grooves, a cutting bit having a socket to receive the end of said shank and projections in said socket for interlocking engagement with said grooves. 15

JOHN RONALD MACDONELL.
